UNITED STATES PATENT OFFICE.

AUGUST C. DITTRICH, OF CHICAGO, ILLINOIS.

COIN-CONTROLLED MECHANISM.

Application filed May 14, 1920. Serial No. 381,249.

To all whom it may concern:

Be it known that I, AUGUST C. DITTRICH, a citizen of the United States, residing at Chicago, in the county of Cook and State 5 of Illinois, have invented certain new and useful Improvements in Coin-Controlled Mechanism, of which the following is a specification.

This invention relates to coin released 10 mechanism, and more particularly to coin released phonographs, though its use is not limited to such instruments.

Among the objects of my invention are to improve upon and to simplify the releasing 15 mechanism of coin controlled devices; to encourage thrift; to provide means whereby the purchaser of a machine may be caused 20 to pay for same as he uses it; and such further objects, advantages and capabilities as will later more fully appear.

My invention further resides in the combination, construction, and arrangement of parts illustrated in the accompanying drawings, and while I have shown therein preferred embodiments of my invention, I desire it to be understood that the same are intended to be illustrative only and not as limiting my invention.

In the drawings annexed hereto and forming a part hereof, Fig. 1 is a fragmentary perspective view of a phonograph with one form of my invention applied thereto, Fig. 2 is a similar view with another form of my invention applied thereto, Fig. 3 is a 30 plan view of a portion of Fig. 1, Fig. 4 is a vertical section of the coin box and locking mechanism shown in Figs. 1 and 3, Fig. 5 is a vertical section at a right angle to the section of Fig. 4 and substantially along the line 5-5 of said figure, Fig. 6 is a cross sectional view substantially along the plane indicated by the line 6-6. Fig. 4, Fig. 7 is a plan view similar to Fig. 3, but showing a modified form of my construction applied 40 to the machine, this corresponding to Fig. 2, Fig. 8 is a vertical section of the construction shown in Fig. 7, Fig. 9 is a vertical section at a right angle to that shown in Fig. 8, and Fig. 10 is a combined transverse section and plan to show the relative position of certain parts of the mechanism shown in Figs. 8 and 9.

Referring in detail to the annexed drawings P designates the phonograph, T the phonograph table carrying the record R,

while C is the controlling mechanism comprising my present invention.

The coin control mechanism, shown in Figs. 1 and 3 to 6 inclusive, comprises a box 1 having a cover 2, hinged thereto and held in closed position by means of a lock 3. This box may be secured to a fixed part of the mechanism to be controlled, by means of screws 4, and in such position that the controlling element 5 may project out thru a hole in the box and engage the movable part whose motions are to be controlled thereby. In this instance element 5 is a brake adapted to engage the flange of a phonograph turn table T to prevent same from rotating. This member 5 is held, in this instance, by a lever 6 resiliently mounted, pivoted at 7 and acted upon by a spring 8. As seen in Fig. 4 lever 6 is bent upwardly to form a loop in which is secured one end of brake 5. This upwardly bent portion of lever 6 is slotted at 9 for the reception of one end of a bell-crank lever 10, pivoted at 11 and actuated to locking position by means of a spring 12. The other end of this bell-crank lever extends laterally into a position to be engaged by a coin 14, inserted thru a slot 15 in the cover of the box 1. Inside of the box and pivoted at 16 is a lever 17 carrying a flat channeled member 18, thru which the coin passes to unlock the locking member. Lever 17 has a handle 19 projecting outwardly thru one side of the box 1, whereby the lever may be manually actuated. Lever 17 is normally held in raised position by means of a spring 20 secured to the lever and to the box.

It will be seen from Fig. 5 that when lever 17 is actuated downwardly by means of handle 19 its lower projection 22 will miss the end 13 of lever 10, and will also miss pin 21 carried by the end of this lever. However, if a coin 14 be inserted thru slot 15 and permitted to roll downwardly, it will stop between pin 21 and the concave upper wall of channel 18, so that as said channel member is actuated downwardly by the handle 19, pin 21 will be forced downwardly and the lower arm of bell crank lever 10 will be forced out of engagement with slot 9 in lever 6, whereby the same is released to be so actuated that brake 5 moves away from the phonograph turntable. When handle 19 is released lever 17 moves upwardly under the tension of spring 20,

releasing coin 14 so that the same falls on the inclined member 23 and slides into box 24 through an opening in the side thereof. When the record has all been played lever 6 is moved over into position so that the 5 brake engages the turntable and stops the rotation thereof. When this happens lever 10 will snap into place in slot 9 thereby locking the brake against the edge of the turntable, thus necessitating the use of another 10 coin to release the same when it is desired to play another record.

In the form described above the control 15 mechanism is in the nature of an attachment to be applied to the top of the phonograph adjacent the turntable, while in the form shown in Figs. 2 and 7 to 10 inclusive it is built into and forms a part of the machine controlled. In this form the top 25 of the box 26 has pivoted thereto as at 27 the lever 28, which has projecting from one end thereof a brake member 29. Projecting downwardly from one arm of this lever is a pin 30, which extends thru a slot 31 in 30 the top of the box. Another pin 32 secured to this lever extends thru another slot in the top of the box and is engaged by a spring 33 which actuates the lever to release the brake from the flange of the turntable.

Pin 30 extending through slot 31 in the 35 box cover normally engages a hole in a resiliently mounted member or lever 34, which has one end bent downwardly and laterally to lie in the path of the coin 14 when same is inserted thru slot 15 and passes downwardly thru tubular member 18 as in the preceding example. The laterally projecting portion 35 of member 34 cooperates with the upper concave surface of 40 member 18 to hold the coin 14 in position so that when arm 19 is moved downwardly member 35 and consequently the end of member 34 will likewise be moved downwardly to release pin 30 on lever 28, so 45 that said lever may be actuated by spring 33 to release the turntable. The dotted lines in Fig. 10 extending from pin 30 and appearing as a slot, indicate the path of movement of pin 30 when same is released 50 by movement of the resilient member 34.

In this form a portion of one side of the phonograph is cut out and hung on hinges so as to form a door which may be locked by means of a lock 3. Hung on the inside 55 of this door is a box 37, which enters box 26 by means of a hole in one side thereof as shown in Fig. 8. It is obvious that the purpose of this box 37 is to catch the coins inserted thru slot 15, when same are released 60 by the actuation of the locking mechanism. The door 36 may be a metal plate hinged to the side of the phonograph cabinet, as shown in Fig. 8.

It is apparent that if the machines are 65 sold on the partial payment plan, to be

paid for as used, the merchant may retain the keys to the cash boxes and send out an attendant periodically to open the box and remove the coins therefrom, or the box B shown in Fig. 1 may be made readily detachable so that same may be taken off and carried to the store to be opened and emptied of its contents. If this is used as a device to encourage thrift, the bank may retain the keys and send out someone periodically to collect the cash and enter the amount as a deposit in the individual's pass book. If the box shown in Fig. 1 is made readily removable, the individual may remove same and take it to the bank, have it opened and emptied of its contents, the amount being entered on the pass book as a credit. This device may have other uses, the foregoing being merely suggestions as illustrative of uses to which same may be put.

Inasmuch as there are various ways in which the box shown in Fig. 1 may be made readily detachable, I will not attempt to describe them in detail, suffice it to say that the top of the phonograph cabinet may be perforated for the reception of screws, which may be passed upwardly to enter screw threaded perforations in the bottom of the box C, or the box may be provided with lugs which may extend downwardly thru the top of the phonograph cabinet and be fastened in place on the inside of the top by any suitable means such as screws and washers or screws and a perforated plate, the screws passing thru the perforations in the plate and into the lugs on the bottom of the box, or slotted plates slideable on the underside of the top of the phonograph cabinet and engaging in slots in the downwardly extending lugs on the bottom of the box. There are various other ways in which the same purpose could be accomplished, without departing from the spirit of my invention, and I will, therefore, not enter into a further detailed description thereof.

It is, of course, understood that the specific description of structure set forth above may be departed from without departing from the spirit of my invention as set forth in this specification and the appended claims.

Having now described my invention,

I claim:

1. In a mechanism of the character described, having a movable element to be controlled and a brake for controlling the movement thereof, the combination of a lever carrying said brake, a lever to hold said first named lever in position so that the brake will prevent movement of the member to be controlled, a third lever carrying a tubular member adapted when it does not contain a coin, to be actuated without actuating said second named lever, but adapted when it does contain a coin to co-operate therewith

to actuate said second named lever for the release of the first named lever.

2. In a mechanism of the character described, a box having an opening in one side thereof, a lever pivoted in said box and carrying a brake which extends out thru said opening in the side of the box, a second lever pivoted to the inside of the box and adapted to engage the first lever to hold the same substantially immovable, a third lever pivoted on the inside of the box and adapted to be actuated from the exterior thereof without actuating said second named lever, the third named lever carrying a tubular member adapted to receive a coin and having a part adapted to co-operate with a part of the second named lever to hold said coin in a definite position and to co-operate therewith for the release of the first named lever, when the third lever is actuated.

3. In a structure of the character described, a spring pressed lever carrying a brake and having means thereon adapted to be engaged by a second member whereby said lever may be prevented from movement upon its pivot, a member adapted to prevent the movement of the lever, a coin receiving tube adapted to co-operate with said last mentioned member to hold a coin, means projecting from the coin receiving tube whereby the latter may be moved and thru co-action of a coin it may cause movement of the lever retaining member, and resilient means to normally hold the coin receiving tube in nonactuated position.

4. In a mechanism of the character described, a box having a top provided with a coin receiving slot, a lever mounted inside of said box and carrying a coin receiving tube having an open end thereof in registry with the slot in the top, a resiliently mounted member in the box in proximity to the tubular member and having a projection thereon extending adjacent the exit opening of said

tubular member, said tubular member having a portion thereof adapted to co-operate with the projection on the resiliently mounted member to engage and hold a coin whereby said resiliently mounted member may be actuated by actuation of the lever, and a spring pressed brake carrying lever adapted to be locked by said resiliently mounted member so that the brake may be held in braking position.

5. In mechanism of the character described, a box having a top, a brake carrying lever pivotally mounted on said top, resilient means for actuating said lever, means on said lever extending thru said box top, and adapted to be engaged by means inside of the box so that the lever may be locked in such position that the brake will act as such, a resiliently mounted lever inside of said box adapted to engage the means on said first named lever, a pivotally mounted coin receiving tube within said box having entrance and exit apertures, said resiliently mounted lever inside of said box having a projection thereon lying adjacent the exit aperture of the coin receiving tube and co-operating with the tube and a coin upon movement of the former to cause release of the first named lever so that the brake may be released from active position.

6. In a mechanism of the character described, a box carrying a lever provided with a brake extending outside the box, said box also carrying a lever provided with a coin receiving tube, and connections between the coin receiving tube and the first named lever such that when there is no coin in the tube the first named lever cannot be actuated upon the actuation of the second named lever, but when there is a coin in the tube such actuation can be caused.

In witness whereof, I hereunto subscribe my name to this specification.

AUGUST C. DITTRICH.
